Inventor
Ferdinand Henze
By his atty # UNITED STATES PATENT OFFICE.

FERDINAND HENZE, OF SALZKOTTEN, GERMANY.

DEVICE FOR PREVENTING EXPLOSIONS.

SPECIFICATION forming part of Letters Patent No. 651,353, dated June 12, 1900.

Application filed August 15, 1899. Serial No. 727,294. (No model.)

To all whom it may concern:

Be it known that I, FERDINAND HENZE, a subject of the King of Prussia, Emperor of Germany, residing at Salzkotten, near Paderborn, 5 in the Kingdom of Prussia, Germany, have invented certain new and useful Improvements in Apparatus or Devices for the Prevention of Explosions in Vessels Filled with Easily-Ignitable Liquids, (for which I have applied 10 for patents in England, dated July 12, 1899; in Germany, dated April 6, 1899, and in Austria, dated July 14, 1899,) of which the following is a specification.

The device about to be described serves to 15 prevent explosions in vessels filled with liquids of a dangerous character, owing to their liability to become ignited. The device is so constructed as to be capable of insertion into the vessel in the same way as a plug and during 20 the transport of the vessel will keep the same completely closed, while on emptying the vessel the gases that may have become developed will be allowed to escape at a certain determined degree of pressure.

25 In the accompanying drawings, Figure 1 represents in longitudinal section a vessel provided with an apparatus or device of the kind specified. Fig. 2 represents the same apparatus on a larger scale. Fig. 3 is a cross-section on the line A A of Fig. 2, and Fig. 4 is a modified form of said apparatus or device.

As seen readily from the accompanying drawings, the device consists of a cylinder *a*, formed of wire-net of a somewhat fine mesh, 35 and made from any suitable metal or alloy and closed at the lower end. Within the wire-net cylinder *a* is a protecting-shield *b*, which is provided with perforations and projections, the latter being so arranged that no damage 40 can be caused to the cylinder *a*. The tubular internal shield *b* serves to support the light wire-gauze cylinder *a* and maintain its shape. It also serves to protect the gauze-cylinder 45 from injury, particularly from sticks or objects inserted through the open top. At its upper portion the cylinder *a* carries a solid metal tube *c*, provided, as seen from the drawings, with a flange *d*, by means of which the apparatus is secured to the side of the containing vessel by means of screws in any suitable manner. In the interior of the tube *c* is

a suitable plug or valve *f*, which will open automatically at a certain given pressure of gas and may be of any desired construction. The upper portion of the tube *c* is provided 55 with an exterior screw-thread on which is screwed a protecting-cover *g* to prevent an accidental opening of the plug *f* during transport of the containing vessel.

The above-described apparatus or device 60 will preferably be made of a length equal to the diameter of the cask or vessel to which it is to be applied, so that the lower end of the same may be fastened to the opposite side or wall of the cask, as may be seen from Fig. 2. 65

When the cask provided with its protecting screw-cap *g* is to be emptied, the protecting-cap *g* is first unscrewed and then the plug *f* is removed, so that the necessary air entering through the tube *c* can reach the interior 70 of the vessel, so as to allow of the emptying thereof. Should, during this operation, any flame strike into this hole or opening, only that portion of the combustible liquid can become ignited which is inside the protecting- 75 shield *b* or inside the cylinder *a*, as the passage of the flame to the other parts of the vessel will be prevented by the wire-netting. After a certain portion of the liquid has been extracted from the vessel the plug *f* is re- 80 placed in the tube *c*, so as to prevent the escape of gases generated by the liquid. If, however, the said gases become collected at an excessive pressure, the plug *f* will be lifted 85 and opened thereby, so that they may freely escape, and therefore a bursting of the cask or vessel through excessive gas-pressure will be rendered impossible.

It is not absolutely necessary that the perforations of the protecting-shield *b* should be 90 formed in the manner shown at Fig. 2. They may, on the contrary, be of any suitable shape—for instance, as represented at Fig. 4. Instead of the plug *f* a valve of any suitable form may be used. 95

What I claim, and desire to secure by Letters Patent of the United States, is—

1. A safety device for oil-barrels &c., consisting of a gauze-wire cylinder closed at one end and provided at the other end with a valve 100 adapted to open at a given pressure, said device being adapted to be inserted in the bar-

rel with its valved end located in the opening therein.

2. A safety device for oil-barrels &c., consisting of a gauze-wire cylinder closed at one end and provided at the other end with a valve adapted to open at a given pressure and a strengthening-tube located within the gauze-wire cylinder.

3. The combination with the cask or barrel, of a gauze-wire cylinder, arranged therein, closed at the bottom and having its upper end open and communicating with an aperture in the cask or barrel, a valve located in said open end, and a removable cap or cover over said valve.

4. The combination with the cask or barrel, having an aperture a tubular piece *c* fitted in said aperture, a valve *f* in said tubular piece,

and a gauze-wire cylinder *a* located within the cask or barrel, fitted to said tubular piece at its upper end and having its lower end closed.

5. The combination with the cask or barrel, having an aperture a tubular piece *c* fitted in said aperture, a valve *f* in said tubular piece, a gauze-wire cylinder *a* located within the cask or barrel fitted to said tubular piece at its upper end and having its lower end closed, and a strengthening-piece *b* within said gauze-wire cylinder.

In testimony whereof I have hereunto set my hand in the presence of two witnesses.

FERDINAND HENZE.

Witnesses:

WOLDEMAR HAUPT,
ALEX. SCHMIDT.
